UNITED STATES PATENT OFFICE.

UMBERTO MARCHI, OF RIVAROLO, LIGURE, ITALY.

TUBE-ROLLING MILL.

Application filed July 13, 1921. Serial No. 484,524.

To all whom it may concern:

Be it known that I, UMBERTO MARCHI, a subject of the King of Italy, and residing at Rivarolo, Ligure, Italy, have invented 5 certain new and useful Improvements in Tube-Rolling Mills, of which the following is a specification.

This invention relates to tube rolling mills.

10 It is essential for the effective operation of tube rolling mills of the Pilger step system (Perrin's process) or any other system in order to obtain a smooth, homogeneous rolling free from bulbs, unevennesses and rolling 15 jumps, that means be provided for insuring a constant and uniform feed of the billet at each revolution of the rolls it being one of the objects of the invention to provide such means and an additional object to provide 20 means for permitting an exact and immediate adjusting of the upper roll with respect to the lower roll and a rigid fixation of this roll after each displacement.

According to the present invention in 25 order to obtain the constant feeding of the tubular billet a bored block is arranged in alignment with the axis of the grooves of the rolls so as to be adjustable in the vertical direction but not in the horizontal direction 30 and is fastened on the housings of the mill so that the inner end thereof bears against the surface of the rolls, the said rolls at each revolution pulling the billet along for a length equal to the semiperipheral rolling 35 length of the rolls in reducing a tubular portion on the billet and are subsequently disengaged from the billet so that the latter is suddenly advanced for the length of the rolled portion, then stopped against the 40 mouth of the block, thus insuring an equal feeding at each revolution of the rolls.

According to the present invention the adjustment of the upper roll is obtained in 45 such a manner that its supports, which are movable within vertical guides of the housings of the mill, are coupled by rods to two hydraulic single acting cylinders vertically mounted upon the top of the side frames the cylinders tending to continuously maintain the upper roll in an elevated position, while a horizontal double acting hydraulic cylinder with a cross sectional area of the bore larger than the total cross sectional area 50 of the bores of the vertical cylinders is arranged between the side frames of the mill and provided with wedge shaped extensions

situated on each side of the cross head of its piston rod so as to move in a direction at right angles to the axis of the rolls, the said extensions resting upon inclined surfaces on 60 the supports of the upper roll so that in admitting water to the front or back of the piston it will displace the wedge shaped extensions along the inclined surfaces of the supports to lower the supports or allow them 65 together with the upper roll to move upwardly under the traction effect of the vertical cylinders only.

An embodiment of the invention is shown by way of example in the accompanying 70 drawings, in which:—

Fig. 1 is a front elevation of a tube mill of the Pilger system partly in vertical section.

Fig. 2 is a vertical longitudinal section 75 taken on line 2—2 of Fig. 1, and,

Fig. 3 is a rear elevation of the mill.

In these figures similar characters of reference indicate corresponding parts. A steel block 1 having a bore of a diameter of 80 some millimeters larger than the outside diameter of the tube to be milled is arranged between the two housings 2 of the mill and has its axis maintained in alignment with the axis of the grooves of the rollers by 85 means of two springs 3 which pull on the block in opposite directions. The block 1 slides with its inner end on the surface of the rolls and is slidably mounted between the housings by means of two ribs 4 which 90 are engaged by corresponding grooves of the block and thereby prevent backward movement of the block by reason of the blows which the same receives during the rolling operation.

The rolls 5 rotating in the direction of rotation indicated by the arrow, pull the billet 6 along for a length equal to the semi-peripheral rolling circumference of the roll and mill the billet for such a length. During 100 the second semi-peripheral circumference the rolls are disengaged from the billet allowing the latter to suddenly advance while the rolled portion of the billet immediately passes through the bore of the block 105 until the shoulder of the unreduced portion of the billet presses against the mouth of the block. In repeating this operation the semi-peripheral rolling surfaces intermittently grasp the billet, mill it, and leave it to advance 110 until the whole billet is reduced to a tube. With this device an excessive feeding

- of the billet is made impossible and the rolling is effected in a smooth homogeneous, and uniform manner without unevennesses, displacement of material and rolling jumps.
- 5 7 are the supports of the upper roll arranged so as to be movable upon vertical guides provided on the housings of the mill, the supports being provided at the top thereof with relatively large inclined surfaces.
- 10 On the tops of the housings are vertically arranged single acting hydraulic cylinders 8 which constantly under a uniform water pressure by means of a conduit connected at 9 so as to maintain the pistons 8' of the cylinders 8 displaced at the upper end of the piston travel. The pistons are connected with bars 10 in turn, coupled by the rods 11 with the support 7. By this means the supports 7 and therefore the upper roll are constantly kept spaced from the lower roll and thereby prevented from being rotated on the lower roll.
- 15

Between the two housings there is horizontally arranged a second hydraulic cylinder 12 with double acting piston 13. The piston rod 14 is connected with a cross head 15 bearing laterally on projecting key shaped extensions 16 which in their turn take their position upon the inclined surfaces 20 of the supports 7 and fill the width between the vertical guides of these supports. The cross sectional area of the bore of the horizontal water cylinder 12 is larger than the total cross sectional area of the 25 bores of the vertical cylinders 8.

In order to lower the upper roll which on account of the traction effort exerted on its supports by the cylinders 8 is in its highest vertical position, water is admitted through 30 the hole 17 in the cylinder 12. The cross-head 15 now causes the two wedges or tapered blocks 16 to be displaced along the inclined surfaces of the supports and to push the supports downwardly. In maintaining the water pressure in this cylinder by means of the hole 17 the upper roll is lowered until it rolls upon the lower one or the same is stopped as desired at any intermediate position according to the quantity 45 of water admitted and in each position given to the movable roll with these hydrau-

lic means a perfectly rigid fixation is obtained.

In order to again raise the upper roll, water is admitted through the hole 18 at the 55 other end of the cylinder and upon the other side of the piston, ejecting the water previously admitted across the hole 17. The water pressure now forces the piston 13 to its retracted position allowing the supports 60 and the upper roll to again rise under the traction effort exerted by the vertical hydraulic cylinders.

It is to be understood that the adjusting device of the upper roll according to the 65 present invention instead of being applied to a tube rolling mill of the Pilger step system may also be applied to other types of mills.

In mills having the housings arranged relatively wide distances apart, one cylinder for each housing may be provided and in this case these different horizontal cylinders may be connected to each other like communicating receptacles in order to obtain contemporaneously in all cylinders the same effect on the pistons. 70 75

Having thus fully described the invention what is claimed as new and desired to be secured by Letters Patent is:

A tube rolling mill including in combination, a main support, ribs formed on said support, rotatable grooved rollers mounted within the support, means for effecting a constant feeding of a billet at each revolution of the rollers including a block provided with a bore having a diameter slightly larger than the exterior diameter of the tube to be rolled and also provided with longitudinal grooves in the opposite side edges 90 thereof for slidable engagement with the ribs on the main support and for preventing lateral movement of the block relative to the rollers, the block being arranged to embrace the side surfaces of the rollers, and 95 resilient means on the main support and associated with the block for maintaining the bore of the block in alignment with the axis of the grooves of the rollers.

In testimony whereof I have signed my 100 name to this specification.

UMBERTO MARCHI.
